H. BULLOCK.

SOLE.

APPLICATION FILED OCT. 24, 1916.

Patented Dec. 31, 1918.

INVENTOR:
HARRY BULLOCK,

Emery, Footh, Jamay & Cheney
Attnys.

UNITED STATES PATENT OFFICE.

HUGH BULLOCK, OF ANDOVER, MASSACHUSETTS, ASSIGNOR TO CONVERSE RUBBER SHOE COMPANY, OF MALDEN, MASSACHUSETTS, A CORPORATION OF MASSACHUSETTS.

SOLE.

1,289,106.

Specification of Letters Patent. Patented Dec. 31, 1918.

Application filed October 24, 1916. Serial No. 127,487.

To all whom it may concern:

Be it known that I, HUGH BULLOCK, a citizen of the United States, and resident of Andover, in the county of Essex and Commonwealth of Massachusetts, have invented 5 an Improvement in Soles, of which the following description, in connection with the accompanying drawings, is a specification, like characters on the drawings representing 10 like parts.

This invention relates to soles for athletic shoes and other purposes.

The character of the invention may be best understood by reference to the following 15 description of an embodiment thereof shown in the accompanying drawing, wherein,—

Figure 1 is a side elevation of the shoe shown herein as embodying the invention; 20 Fig. 2 is a plan of the bottom of the sole;

Fig. 3 is a vertical, transverse section through the ball of the sole; and

Fig. 4 is a vertical, transverse section 25 through the heel of the sole.

Referring to the drawing, 1 designates the upper of an athletic shoe provided with a sole 3 embodying the invention. This sole may be of rubber or other suitable material formed to present series of crossing ribs 5 30 having rounded edges and extending obliquely to the length of the sole. Between these ribs are spaces or pockets 7 adapted with a pneumatic suction action to grip the floor and tend to prevent slip of the sole 35 relatively thereto.

These ribs and pockets preferably are located in the bottom of both the ball and heel of the sole and the outer edges of the areas thus formed may be bordered by margins 40 of solid rubber.

To further contribute to prevention of slip, webs or ribs 11 of thin rubber may be provided in and extend across certain of the pockets longitudinally of the sole. Preferably they cross those of the pockets adjacent the inner edge of the sole and thus are localized beneath the portion of the foot of the wearer which bears the brunt of the weight. These webs preferably are thinner 45 than the ribs described and have greater resilience than said ribs and desirably coöperate therewith to prevent slip of the sole.

One important field of use of the shoe described is in playing basket-ball. In this 50 game the player must frequently suddenly

change his direction of movement and his effectiveness as a player is substantially increased if he is able to rely upon his shoes to prevent slipping on the smooth floors which are used in this game.

The shoe described lends itself admirably for this purpose. The oblique ribs tend to prevent slip in all directions, but they are preferably of substantial thickness to furnish the necessary wear-resisting qualities 65 and therefore in and of themselves do not obtain the desired grip on the floor especially when the player suddenly changes his direction of movement. For example, it may be supposed that the player is running in a straight line and suddenly shifts sharply to the right. In doing so, he exerts a pronounced pressure or push of the left foot which comes principally upon the portion of the sole adjacent the inner edge 70 thereof. This will press the thin edges of the elastic webs against the floor and they will yield and stretch rather than slip along the floor. This yield will continue until they contact with and are backed by the ribs 75 of the pocket adjacent thereto. Thus they effectively serve to check slipping of the sole.

Since the brunt of the wear will come upon the thicker and more rigid ribs, they 80 will desirably protect and prolong the life 85 of the slip-resisting webs.

While the sole has been described more particularly with reference to an athletic shoe it will be understood that its field of 90 usefulness is not restricted thereto.

Having described one embodiment of the invention without limiting the same thereto, what I claim as new and desire to secure by Letters Patent is:—

1. A sole having elastic ribs in the bottom thereof forming slip-resisting pockets, and slip-resisting webs extending across said pockets of greater elasticity than said ribs.
2. A sole having a series of elastic slip-resisting ribs located adjacent the inner edge thereof, said ribs being of greater elasticity than other bearing portions of the sole.
3. A sole having projections forming pockets on the bottom thereof and provided with a series of elastic slip-resisting webs on the ball and heel thereof adjacent the inner edge of the sole, said webs being of greater elasticity than the projections forming the pockets.

4. A sole having a ball and heel provided with slip-resisting pockets, and slip-resisting elements of lesser cross-sectional area than the side walls of said pockets and extending longitudinally of the sole across a plurality of said pockets.

5. A sole provided with a ball having a solid margin and a panel therein containing ribs forming slip-resisting pockets, and elastic slip-resisting elements in said pockets, said slip-resisting elements being of lesser

cross-sectional area than the side walls of said pockets.

6. A sole having slip-resisting pockets 7 therein and a slip-resisting rib 11 extending 15 longitudinally of the sole and common to a plurality of said pockets, said rib 11 being of lesser cross-sectional area than the side walls of said pockets.

In testimony whereof, I have signed my 20 name to this specification.

HUGH BULLOCK.
